UNITED STATES PATENT OFFICE.

EDWARD DAVIS BEAN, OF ARLINGTON, MASSACHUSETTS, ASSIGNOR TO THE CYCLIST'S AND SPORTSMAN'S GUN AND RIFLE COMPANY, OF KITTERY, MAINE.

CANE-GUN BARREL.

SPECIFICATION forming part of Letters Patent No. 380,975, dated April 10, 1888.

Application filed August 29, 1887. Serial No. 248,149. (No model.)

To all whom it may concern:

Be it known that I, EDWARD DAVIS BEAN, of Arlington, in the county of Middlesex and State of Massachusetts, have invented certain 5 new and useful Improvements in Cane-Gun Barrels, of which the following is a specification.

This invention has for its object to provide a gun-barrel which shall be sufficiently light 10 to adapt it for use in a cane-gun, and at the same time sufficiently stiff and inflexible; and to this end my invention consists in a gun-barrel composed of a light inner tube of metal constituting the barrel proper, a tube of wood 15 or other light non-metallic material inclosing the inner tube, and an inclosing-tube of leatheroid or equivalent fibrous material closely fitting and inclosing the wooden tube, the whole constituting a composite tube so combining the 20 qualities of lightness, stiffness, and strength as to make it particularly desirable as the barrel of a cane-gun.

Of the accompanying drawings, forming a part of this specification, Figure 1 represents 25 a longitudinal section of my improved gun-barrel. Fig. 2 represents a section on line *x*-*x*, Fig. 1.

The same letters of reference indicate the same parts in both figures.

30 In carrying out my invention I take a comparatively light tube, *a*, of steel or other suitable metal, the inner surface of which may be finished like the bore of an ordinary gun or rifle barrel. Said tube is externally threaded at its ends, so that the stock of the gun can be 35 screwed upon one end and a tip or ferrule, *b*, upon the other end. Before the tip or ferrule is applied I drive upon the steel tube *a* an intermediate tube, *e*, of any suitable light and 40 strong wood or other non-metallic material. Said wooden tube is formed to fit very closely on the steel tube, considerable force being required to drive it to place on the latter. The 45 external surface of the wooden tube is preferably tapered, as shown, its larger end being nearest the stock of the gun.

A flange, *c*, is placed upon the steel tube *a* at one end of the wooden tube and bears against the latter. The tip or ferrule *b* is screwed upon 50 the opposite end of the steel tube and bears

against the opposite end of the wooden tube, as shown in Fig. 1. I then apply to the outer surface of the wooden tube a sheath or tube, *g*, of leatheroid, the same being applied when it is in a soft and pliable state caused by soaking it in water. The leatheroid tube in drying shrinks slightly, and is thereby caused to adhere very closely to the wooden tube, the size of the leatheroid tube being such that when it is in a softened condition it will be just 60 enough larger than the wooden tube to enable it to be forced onto the latter without undue resistance.

I use that variety of leatheroid which when dry becomes very hard and is susceptible of 65 a polish. After the leatheroid tube has dried and shrunk firmly upon the wooden tube its outer surface may be polished to impart a desirable finish to the gun-barrel.

The leatheroid casing is preferably extended, 70 as shown in Fig. 1, so that it covers the periphery of the collar *c*.

The gun-barrel thus constructed is much lighter than a solid metal barrel of equal external diameter, and is sufficiently strong and 75 stiff to meet all the requirements of a cane-gun barrel.

The leatheroid casing being water-proof and tightly contracted upon the wooden tube protects the latter from moisture.

The wooden tube *e* and leatheroid casing *g* shrunk thereon constitute a light and stiff casing for the steel tube, preventing the latter from being indented and bent and from being ruptured by the explosion of the cartridge.

I prefer leatheroid as the material for the outer casing, because it is tough, rigid, susceptible of a polish, and capable of contracting from a water-softened condition, so that it will firmly grasp the wooden tube.

The leatheroid tube may be formed on the wooden tube, if preferred, instead of being formed separately and afterward applied to the wooden tube.

It is obvious that the intermediate tube, *e*, 95 may be made of pulp or some other equivalent material, instead of natural wood.

I claim--

1. The improved gun-barrel composed of the inner metal tube, the intermediate tube inclos- 100

ing the metal tube, and the external water-proof binding case or tube covering the intermediate tube, as set forth.

2. The improved gun-barrel composed of the inner metal tube, the intermediate tube inclosing the metal tube, and the external case of leatheroid shrunk upon the intermediate tube, as set forth.

3. The improved gun-barrel composed of the inner metal tube, the collar, and tip or ferrule applied to said tube, the intermediate tube inclosing the metal tube between said collar

and tip, and the external case of leatheroid shrunk upon the wooden tube and extended beyond the end of the latter upon the collar, as set forth.

In testimony whereof I have signed my name to this specification, in the presence of two subscribing witnesses, this 24th day of August, 1887.

EDWARD DAVIS BEAN.
